Term of patent 3½ years

(Cl. D72—1)

FIG. 1

FIG. 2

FIG. 3

FIG. 4

FIG. 5

FIG. 1 is a top view of the distress signal, showing our new design;

FIG. 2 is a left side view of the distress signal of FIG. 1;

FIG. 3 is a front view of the distress signal of FIG. 1;

FIG. 4 is a right side view of the distress signal of FIG. 1; and

FIG. 5 is a bottom view of the distress signal of FIG. 1.

The stippling in all the figures is representative of the light reflecting character of the surfaces of the signal.

We claim:

The ornamental design for a distress signal for automobiles, substantially as shown and described.
